COAL STOKER

Laurence Edward Barringer, Carnegie, Pa., assignor of one-half to Philip Hubacher, Carnegie, Pa.

Application December 28, 1935, Serial No. 56,563

4 Claims. (Cl. 198—64)

The present inventive conception relates to an especially important improvement which is particularly, but not necessarily, well adapted for incorporation in a coal stoker such as is used for feeding or delivering coal or equivalent fuel to a boiler or furnace, or the like.

As will be evident, however, from the succeeding description, accompanying drawings, and the claims the gist of the invention is predicated upon what may be explicitly referred to as a new and novel conveyor such as may be satisfactorily incorporated in a more or less conventional stoker system, wherein the conveyor is substantially clog-proof.

It is a matter of common knowledge that coal and the like introduced into the supply hopper is laden with extraneous objects and materials, such as pieces of wire, screen, nails, and so on, which tend to obstruct the free feed and flow from the hopper through the delivery tube and into the boiler. Observation discloses that the stricture in the delivery conduit, of which the base of the hopper forms a portion, causes the lodging material to pack and clog at the point of egress from the base of the hopper. Under the circumstances, an unusually stout feed screw and a sturdy assemblage of parts is essential to withstand this stress and strain. Even so the structure is frequently incapable of providing a requisite continuity in the feed action and a break-down occurs.

I have therefore discovered the need for the provision of a new type of feed screw which provides the requisite clearance to render the assemblage substantially obstruction-proof.

Other features and advantages obviously linked with the special adaptation and improvement will become more readily apparent from the following description and accompanying drawings.

In the accompanying pictorial drawings, wherein like numerals are employed to designate corresponding parts throughout the views:

Figure 1 is a complete elevational assemblage view disclosing the coordination of the boiler and stoker and illustrating, so far as external appearance is concerned, that the arrangement appears standardized or normal.

Figure 2 is a view, partly in section, and partly in elevation showing the improved worm or feed screw and associated features, perfected in accordance with my idea.

Figure 3 is a fragmentary elevational view showing the clearance gap or "break" in the improved conveyor or feed screw.

Figure 4 is an enlarged section taken approxi-

mately on the plane of the line 4—4 of Figure 2 looking in the direction of the arrows with the casing removed and parts of the fin broken away.

Referring now to the general assembly disclosed in Figure 1, it will be observed that the boiler, which may be of any suitable size, is indicated by the numeral 5. The coal stoker, as a unit, is denoted by the numeral 6 and a conveyor propulsion motor is indicated at 7.

Observing now Figure 2, it will be seen that the foundation is indicated at 8, this being of appropriate form and supported on this is the base receptacle 9 of the hopper ensemble. The hopper proper is indicated at 10 and is preferably of customary funnel design although it is here shown as separably mounted as at 11 on the base. The base unit forms a part of the receiving and delivery conduit, the delivery portion of the conduit being in the form of a regular tube or pipe 12. The restricted discharge opening, 13, which affords communication between the base 9 and the tube 12 is the objective which has heretofore, in conjunction with the conveyor, caused accumulation and clogging with a resultant frequent closing down of the stoker system to either make repairs or dislodge the jam occurring at the juncture 13 between the parts 9 and 12.

It has been discovered that by properly constructing the worm or feed screw and ingeniously adapting its features to the restricted outlet 13, the line is rendered substantially obstruction or clog-proof. Broadly then, the novelty has to do with means incorporated in the conduit (parts 9 and 12) which affords the necessary clearance

and relief and at the same time provides the requisite continuity in the feed action. Whereas as this may be accomplished otherwise, the preferred embodiment of the invention is that depicted in the drawings. Here it will be observed that the rotary feed worm shaft, which is of a regulation type, is indicated by the numeral 14 and is connected with the motor at one end and extends through the conveyor tube 12, being mounted for rotation in suitable bearings (not shown).

The helical threads, or impeller fin may be divided into two companion successively co-operable sections 15 and 16, the section 15 being confined in the base 9 and the section 16 in the tube 12. The terminal end portion 17 of the threads on the section 15 is cut off, so to speak, so that the extremity 18 thereof is at right angles to the longitudinal axis of the rotary feed worm shaft 14. Moreover, in practice it is spaced one

inch or more from the restricted outlet or junc-

ture 13. This is sufficient to provide the desired spiral activity and thrust action to forcibly feed the mass of material into the opening 13 and to at the same time compensate for possible clogging because of the clearance provided. In other words, this terminal 18, is aptly fitted to literally press or "cam" the load into and through the orifice 13 to be picked up and carried on by the progressively acting companion screw section 16. The major thread portion of the section 16, indicated at 19, is conventional. It is to be observed, however, that the inmost convolution terminates in close spaced proximity to the intake 13 and is fashioned into what may be conveniently described as a pick-up hook or claw 20. As better shown in Figure 3, the facility with which this hook acts is enhanced by the special formation of the bill 21 and the associated beveled knife-edge 22. This edge has a concave curvature, the outer extremity or tip of the claw being in advance of the root or point where the edge joins the shaft, as the screw rotates.

Looking at the alleged novelty from another viewpoint, it may be simply said that the feeding thread of the conveyor or worm is merely broken to form a gap, the said gap occurring at the junction 13 in such a way as to provide the requisite continuity in the feed. Thus the features 15 and 16 are to be considered separately and collectively, since the fundamental novelty is predicated upon structural means embodied in the conduit (parts 9 and 10 as a unit) wherein the feed screw is constructed at the point of structure to provide progressive feeding and pick-up and to avoid clogging at this vital point.

Emphasis is to be accorded the feature 22 which, as is evident from the drawings, tends to cause obstructions, such as nails and other unyielding objects, to ride radially in toward the axis of rotation or shaft, instead of permitting the objects to ride radially outward to interfere with the effluent action of the load. It is primarily a curvature of this edge 22 which causes the inward cam action.

It is thought that persons skilled in the art to which the invention relates will be able to obtain a clear understanding of the invention after considering the description in connection with the drawings. Therefore, a more lengthy description is regarded as unnecessary.

Minor changes in shape, size, and rearrangement of details coming within the field of invention claimed may be resorted to in actual practice, if desired.

What is claimed is:

1. A conveyor screw comprising a shaft having a helical thread at one end terminating in a

presser fin, the terminal of said fin being blunt and disposed at right angles to the longitudinal axis of the shaft, an additional helical thread on the shaft in spaced relation to said presser fin and having a hooked pick-up element confronting the presser fin. 5

2. A conveyor screw comprising a shaft having a helical thread at one end terminating in a presser fin, the terminal of said fin being blunt and disposed at right angles to the longitudinal axis of the shaft, an additional helical thread on the shaft spaced from said presser fin and having a crooked pick-up element, and said element having a beveled and curved knife-edge in the manner and for the purposes described. 10

3. In combination, a coal hopper formed with an unrestricted opening of constant area in the side adjacent the bottom thereof, a horizontal delivery tube joined to the hopper and registering with said opening, a horizontal shaft extending through said hopper and delivery tube and the opening, a symmetrical helical conveyor fin radiating from the shaft and being interrupted for a space on the shaft extending on each side of the opening, the fin being otherwise continuous throughout the hopper and delivery tube, the interrupted edge of the fin on the hopper side of the opening being radial to push coal and refuse into the opening, the interrupted edge of the fin on the delivery tube side of the opening being concavely curved and formed with a bevelled knife edge having a leading outer extremity to provide a bill to bite into the coal and refuse clogged in the opening and advance the coggings in the path of the fin in the delivery tube. 15

4. In combination, a coal hopper formed with an opening in the side thereof, a delivery tube joined to the hopper having the chamber thereof registering with said opening, a shaft extending through said hopper and delivery tube and the opening, a helical conveyor fin mounted on the shaft and being interrupted for a space on the shaft extending on each side of the opening, the fin being otherwise continuous throughout the hopper and delivery tube, the interrupted edge of the fin on the hopper side of the opening being radially disposed with respect to the shaft to push the coal and refuse into the opening, the tip of the interrupted edge of the fin on the delivery tube side of the opening being in advance of the point where the edge of the fin joins the shaft to provide a leading bill to bite into the coal and refuse clogged in the opening and advance the coggings into the path of the fin in the delivery tube. 20
